UNITED STATES PATENT OFFICE.

CHARLES MILLER, OF PLYMOUTH, INDIANA.

PUMP.

SPECIFICATION forming part of Letters Patent No. 248,490, dated October 18, 1881.

Application filed April 4, 1881. (No model.)

To all whom it may concern:

Be it known that I, CHARLES MILLER, of 5
Plymouth, in the county of Marshall and State
of Indiana, have invented certain new and use-
ful Improvements in Pumps; and I do hereby
declare the following to be a full, clear, and
exact description of the invention, such as will
enable others skilled in the art to which it per-
tains to make and use it, reference being had
10 to the accompanying drawing, which forms part
of this specification.

My invention relates to an improvement in
double-acting force-pumps; and it consists in
the combination of devices, which will be more
15 fully described hereinafter, whereby a double-
acting piston and cylinder are applied to the
side of a straight stock without changing the
straight line of the stock or in any manner in-
terfering therewith further than to place a
20 partition in the stock opposite the lower portion
of the cylinder.

The object of my invention is to construct a
cylinder which can be applied directly to the
side of the straight stock without in any man-
25 ner changing or altering the stock further than
to insert a partition in it at a certain point,
thus enabling me to convert any single-acting
pump into a double-acting one.

The accompanying drawing represents a ver-
30 tical section of my invention.

A represents a common straight stock, such
as is used in all single-acting pumps. Se-
cured to the side of this stock, at any suitable
35 point, is the cylinder B, in which the valveless
piston C is operated by means of any suitable
mechanism secured to the upper part of the
stock. In the stock A, opposite the lower end
of this cylinder, is placed a suitable partition,
40 D, which serves to turn the rising water from
the stock into the lower part of the cylinder
as the piston is worked back and forth. Just
above this partition a valve-port, F, is made,
and through the upper end of the cylinder a
45 second valve-port, G, is made, and through
these two ports the water is forced by the
piston into the stock above the cylinder, so as
to be forced constantly upward. The parti-
tion D extends horizontally outward from the
50 inner side of the stock into the cylinder, be-
yond the bore I of the cylinder, and between
the lower part of the cylinder and this parti-
tion the water-passage J is formed.

In the outer side of the cylinder a vertical
water-way, L, is formed, and from this water-
way are made the two valved ports O, through 55
which the water is alternately drawn into the
bore of the cylinder. As the piston is drawn
upward the water is drawn up through the
stock into the lower part of the cylinder and
through the lower valved port, O, into the 60
lower part of the bore of the cylinder, and
then, when the piston is forced downward, the
lower valved port, O, is closed and the upper
one opened, so that the water will be drawn
from the vertical water-way L into the top of 65
the bore of the cylinder. While the piston is
being forced downward all of the water that
was drawn into the cylinder in its upward
stroke is forced through the lower valve pas-
sage-way into the stock, and as the piston 70
rises all of the water which was drawn into
the bore upon the piston's downward stroke is
forced through the upper valve passage-way
into the stock, and thus the water is alter-
nately drawn into and forced from the opposite 75
end of the bore of the piston in the usual man-
ner.

By means of the construction here shown it
will be seen that a cylinder thus constructed
can be applied to the straight stock of any sin- 80
gle-acting pump, so that it can be converted
into a double-acting one, as described.

I am aware that a cylinder has been placed
between two stocks, or two parts of one, and
this I disclaim. My invention differs from 85
this in the application of a double-acting cyl-
inder to a straight stock.

Having thus described my invention, I
claim—

The combination of a straight stock having 90
the partition D inserted in it, with a cylinder
having a bore for the piston, and a water-pas-
sage, L, with suitable valves, whereby a dou-
ble-acting force-pump is formed, substantially
as shown and described.

In testimony that I claim the foregoing I
have hereunto set my hand this 28th day of
March, 1881.

CHARLES MILLER.
